UNITED STATES PATENT OFFICE

JOSEPH P. ALBIN, OF CINCINNATI, OHIO.

DESIGN FOR A COFFIN.

Specification forming part of Design No. **6,140**, dated September 17, 1872.

Specification of a new Design for Coffins, invented by JOSEPH P. ALBIN, of Cincinnati, in the county of Hamilton and State of Ohio.

My design is represented in the accompanying photographic illustration.

The body of the coffin is made with up-flaring sides and ends, the ends being of rounded or semicircular form. The lid is provided with an elliptical or ellipsoidal opening adapted to expose the face and bust, covered by a cap in the usual way. The remainder of the lid is ornamented with a raised panel or molding, the upper end of which is curved

parallel, or nearly so, with the end of the face opening.

I claim as new—

The design for a coffin, represented in the accompanying photograph, when the lid is formed and ornamented substantially as set forth.

In testimony of which invention I hereunto set my hand.

JOSEPH P. ALBIN.
